RACK ATTACHMENT FOR LAUNDRY TUBS

Leslie W. Larson, St. Paul, Minn.

Application June 25, 1945, Serial No. 601,533

2 Claims. (Cl. 248—150)

1

This invention relates to an attachment for laundry tubs whereby a receptacle may be supported at a convenient elevation above the floor to receive wet clothes or other work from the tubs.

It is an object of my invention to provide a simple, compact and rugged laundry accessory of the character described.

A further object is to afford in a rack of this class a horizontal support adapted to receive clothes receptacles of a wide variety of sizes and to securely support them on the inclined front wall of a laundry tub of either of several common types.

A particular object is to provide such an attachment with inclined tub engaging members adapted to be suspended from hooks engaging the upper edge of the tub wall and having a horizontally extending basket support pivotally connected to the tub engaging members and supported on tension members depending from the wall engaging members beneath the overhang of the inclined tub wall.

A still further object is to provide a rack attachment of the class described which is readily collapsible to compact form for shipping and storage when not in use.

Referring to the accompanying drawing which illustrates, by way of example, a preferred form of my invention;

Figure 1 is an end view of my rack mounted on a tub of common type, the latter being shown in vertical section;

Fig. 2 is a top plan view of the rack separate from the tub;

Fig. 3 is a front elevational view of the same, and

Fig. 4 is a side elevational view, showing the rack members in collapsed or folded position.

In the drawing, Fig. 1, my device is shown attached to a laundry tub of the common type having an inclined front wall 5 and side and back walls indicated by the numerals 6 and 7 respectively. Many laundry tubs of recent manufacture have front walls 5 disposed at an angle of 60 degrees to the horizontal and some old style tubs have front walls as steep as 75 degrees. To engage the outer surface of the front wall 5, I provide spaced, parallel members 8 which are rigidly connected together by cross slats 9. Fas-tened to the upper end portion of each of the members 8 is a hook 10 which is formed to embrace the upper edge of the wall 5 and to support my improved rack on the tub. Projecting horizontally to the front of the tub from the

2

lower ends of the members 8 is a pair of spaced, parallel platform members 11 which are pivotally connected to the members 8 by bolts 12.

Cross slats 13, 14, 15 and 16 rigidly connect the members 11 together, these slats being disposed in spaced parallel relation one to another. A laundry basket 17 or other receptacle for the clothes may be supported on the slats 13, 14 and 15 approximately at the elevation of the tub bottom so that the open top of the basket is approximately at the elevation of the top of the tub. Tension members 18 extend downward from hooks 19 fixed on the members 8 and the lower ends of these tension members are anchored to eyes 20 secured to the members 11 to support the latter in horizontal position at the front of the tub.

In order to adapt my device to support the platform members 8 in horizontal position and on tub walls variously inclined, the tension members 18 are preferably chains having links severally adapted to receive the hooks 19. These chains are long enough so that the members 8 may be disposed at an incline corresponding to that of the particular tub wall on which the device is to be hung. Otherwise, the members 18 may be formed from strap metal or other suitable material and their effective lengths may be made adjustable in suitable manner to provide for changes in the angle of the members 8. As further shown in Fig. 1 the tension members 18 are located beneath the overhanging tub wall 5, so that the entire platform surface which projects to the front of the upper edge of the tub is left free and unobstructed to receive clothes baskets of various sizes and shapes. Thus, as indicated in Fig. 3, a clothes basket 17a which projects beyond the ends of the slats 13, 14 and 15 may be securely supported with its rear side 35 extending along in near proximity to or in contact with the upper edge of the tub wall 5.

A wringer 21 may be used as indicated in dotted lines in Fig. 1 above the upper edge of the wall 5 to receive the wet clothes from the tub 45 after they have been washed and to feed them, after wringing, directly into a basket 17 supported on the platform of my device. When the rack is not needed it may be removed from the tub merely by disengaging the hooks 10 from the wall 5. It may then be collapsed to the compact form indicated in Fig. 4 by merely disengaging the members 18 from the hooks 19 and then pivoting the members 8 backward about the axes of the bolts 12 so that the members 8 extend along 50 the outer surfaces of the platform members 11.

and the hooks 10 are positioned near opposite ends of the slat 14. My device obviates the need for placing clothes baskets on the laundry floors which are often wet and it otherwise promotes cleanliness and facilitates the handling of clothes or other materials in laundry work.

Having described my invention, what I claim as new and desire to protect by Letters Patent is:

1. A rack adapted to be supported on the inclined front wall of a laundry tub comprising, spaced, parallel wall engaging members adapted to extend at an incline and in engagement with the inclined outer surface of said wall, tub engaging hooks projecting from the upper end portions of said members to support them on said wall, parallel platform members pivotally connected to the lower end portions of said wall engaging members respectively and tension members depending from said wall engaging members for supporting said platform members in substantially horizontal position, said tension members being positioned beneath the overhang of said wall and said platform members projecting to the front of said wall and tension members to support a receptacle approximately at the elevation of the tub bottom.

2. A rack for supporting a laundry receptacle on the inclined front wall of a laundry tub comprising, spaced parallel wall engaging members adapted to extend at an incline and in engage-

ment with the inclined outer surface of said wall, tub engaging hooks projecting from the upper end portions of said members to support them on said wall, spaced, parallel platform members pivotally connected respectively to the lower end portions of said wall engaging members, means rigidly connecting said platform members together and tension members depending from said wall engaging members for supporting said platform members in substantially horizontal position, said tension members being positioned substantially entirely beneath the overhang of said wall and being detachable to permit collapsing of the wall engaging members to positions parallel and adjacent to said platform members when the rack is not in use.
